UNITED STATES PATENT OFFICE.

JOSEPH M. ARMSTRONG, OF ALEXANDRIA, VIRGINIA.

BOOK-SUPPORTING DEVICE.

Application filed February 7, 1921. Serial No. 443,085.

To all whom it may concern:

Be it known that I, JOSEPH M. ARMSTRONG, a citizen of the United States, residing at Alexandria, in the county of Alexandria and State of Virginia, have invented certain new and useful Improvements in Book-Supporting Devices, of which the following is a specification.

This invention relates to book-supporting devices adapted for use in connection with book-cases, book-shelves and the like.

When books are snugly or compactly positioned in the existing book-cases, it is difficult to withdraw them, and they can only be removed by gripping the back of the book at the upper edge thereof, which action loosens the leaves and eventually destroys the book. In existing arrangements the outer sides of the books rub against each other during the insertion and withdrawal of the book, thereby mutilating the binding, which action is especially noticeable in the better quality books. It has also been observed that when books are placed in ordinary shelves, the leaves, due to the fact that the book sides are of greater dimension than the leaves themselves, tend to drop to engagement with the shelf thereby exerting a stress on the upper portion of the book-binding which eventually loosens the leaves. In the present book-cases it is also difficult to keep the books in alinement to present a uniform appearance, and when one or more of the books have been removed the remaining books tend to topple over and rest against the adjacent book or side of the shelf thus presenting an unsightly appearance.

An object of this invention is to provide a book-supporting device comprising means for maintaining the books in alinement and always in an upright position upon the shelf, as well as means for slightly spacing the books in order to prevent the books rubbing against each other.

Another object of the invention is to provide means for facilitating the withdrawal of the books from the case or shelf and to provide means for supporting the leaves of each book independently of the side members of the book-cover, thereby relieving the book-cover or back of all stresses while the books are positioned on the shelf.

Another object of this invention is to provide a book-supporting device of generally improved construction, whereby the device

will be simple, durable and inexpensive in construction, as well as convenient, practical, serviceable, and efficient in its use.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

The invention has been illustrated in its preferred embodiment in the accompanying drawings, wherein:

Figure 1 is a perspective view of a portion of the device showing it applied to a shelf of an ordinary book-case, or a book shelving structure;

Figure 2 is a diagrammatic view showing the relation of the guide members of the base and the guide members of the book receiving member;

Figure 3 is a diagrammatic view of the lower portion of the book in its position upon an ordinary shelf, showing the positions assumed by the lower edges of the book leaves;

Figure 4 is a transverse sectional view taken through an ordinary book-case or shelf, showing the book-supporting device applied thereto;

Figure 5 is an enlarged fragmental sectional view taken on a line 5—5 of Figure 4; and

Figure 6 is a horizontal sectional view taken on a line 6—6 of Figure 4.

Referring to the drawings, there is shown a shelf A and a back B of an ordinary book-case, and a base member 1 is positioned upon a shelf A. The base member 1 is provided with a plurality of spaced guide members or tracks 2 which are arranged in pairs and extend transversely of the base member 1. This base member is preferably formed of sheet metal and the tracks or guide members 2 are formed by bending the base 1 upwardly at predetermined points and then bending the metal back upon itself, as shown, thus forming the reinforced guide member or track 2 of double thickness. Those portions of the base 1 that lie between the separate pairs of guide members 2 are slightly spaced from the shelf to provide supporting strips 3, and the remaining

portions of the base engage the shelf A, to which the base is secured by screws or other suitable securing devices 5. Each guide member 2 is inclined outwardly to form overhanging tracks to cooperate with instrumentalities hereinafter disclosed.

A book receiver or book holder is provided and comprises a bottom 6 and opposed side-supporting members or flanges 7. The bottom 6 is bent downwardly and inwardly at points adjacent the side flanges 7 to provide opposed guide members 8 which cooperate with the guide members 2 of the base, thereby providing means for slidably securing the book holder to the base 1. From the lower terminals of the guide members 8 the bottom of the book holder extends outwardly to provide opposed channels 9, and the bottoms of the channels lie below the plane of the main bottom 6 in order to receive the lower edges of the sides C of an ordinary book. By this arrangement the bottom of the book holder is offset to form a central platform 10 to support the leaves D of a book and opposed channels to support the opposed sides C of the book. Thus when a book is placed within the book holder, the leaves D are supported in horizontal alignment which relieves the back E of the book cover of all stress. This is highly advantageous, because it has been observed that when books are placed on an ordinary shelf the leaves D, which are smaller than the sides C, tend to drop to engagement with the shelf thereby causing the lower edges of the leaves to assume the positions shown in Figure 3, which obviously exerts a stress on the back of the book cover which action loosens the leaves and eventually leads to the destruction of the book.

In order that a selected book may readily be withdrawn from the book-case or shelf, means are provided to automatically move the book outwardly a limited distance so that it may be easily grasped and removed. To this end a leaf spring or yieldable actuating member 11 is secured to the base 1 between the tracks 2 of each pair of guide members and has its free end positioned in the path of movement of the rear edge of the bottom 6 of the book holder. A detent is provided for each book holder and comprises a leaf spring 12 having one end secured to the base 1, and the opposed end extends outwardly beyond the front edge of the base to provide a manipulating finger 13, which finger has a shoulder 14 formed at its inner terminal to cooperate with a shoulder or stop finger 15 which is formed by turning a portion of the bottom of the book holder downwardly, as shown.

In use, a book is placed within the book holder and the side flanges 7 engages the opposed sides C of the book and hold it in an upright position, in which position the

leaves are supported by the leaf-supporting platform 10, and the lower edges of the sides C of the book are received and supported by the channels 9. Now the book is pushed rearwardly into the case which causes the book holder to slide upon its guide members until the rear edge of the bottom of the book holder engages the free end of the spring 11. Further pressure against the book will cause the book holder to continue to slide until the shoulder 14 of the spring detent snaps behind the shoulder or stop member 15. In the meantime if the book is not in correct position within the book holder, the rearward pressure exerted against the book after the engagement of the holder with the spring 11, will cause the book to slide rearwardly within the book holder until the lower portion of the book-back E engages the front end of the book holder bottom or platform 10, as shown in Figure 6, therefore causing all the book backs to be positioned in perfect alignment within the case thus presenting a uniform appearance. When it is desired to remove a book from the case or shelf, a slight downward pressure is exerted upon the outer end of the manipulating finger 13, which causes the spring 12 to yield to permit the shoulder 14 to move from engagement with the stop or shoulder 15 of the book holder, which action releases the book holder and allows the spring 11 to slide the book holder and book forwardly. Now the book may readily be gripped and withdrawn from the case.

The book holder may be partly or entirely withdrawn with the book, and when the device is arranged for the complete disengagement of the book holder with respect to the guide members of the base, the guide members 8 of the book holder and the guide members 2 of the base 1 are not arranged in parallelism, but their rear terminals are slightly farther apart than their front ends, as shown in Figure 3. Thus when it is desired to place the book holder within the case, the broad rear terminals of the book holder guide members 8 loosely engage the front terminal of the base guide members 2, which permits the easy engagement of these guide members. But as the book holder is moved rearwardly these guide members more closely engage each other and when the book holder has reached its rearmost position, the separate guide members firmly engage each other, thus insuring a firm support for the book.

When the holder is designed for total disengagement from the base guide member 2, it can be advantageously employed to hold a number of separate papers or pamphlets and the like, and the holder with its contents may be moved to desired places. It is also advantageous to totally disengage the book holders from the base when it is de-

sired to remove a number of books from the case at the same time, and in this event the selected books are supported within the book holders until they are used, thus prolonging the life of the books.

Having thus described the invention, what I claim as new is:—

1. A book holder formed of sheet metal and including a bottom, opposed side flanges extending upwardly from the opposed longitudinal edges of the bottom to engage and support the sides of a book, the bottom being bent downwardly and outwardly at points adjacent the side flanges to define opposed channels for the reception of the lower edges of the sides of the book and to define a leaf-supporting platform between the said channels.

2. A book holder formed of sheet metal and including a bottom, opposed side flanges extending upwardly beyond the highest point of the bottom, the bottom being bent downwardly and outwardly at points adjacent the side flanges to define opposed channels for the reception of the lower edges of the sides of a book and to define a leaf supporting platform between the said channels.

3. A book supporting device including a base, opposed guide members carried by the base, a book holder formed of sheet metal and comprising a bottom, opposed side flanges extending upwardly from the bottom to engage and support the sides of a book, said bottom being bent downwardly and outwardly at points adjacent the side flanges to define opposed channels for the reception of the lower edges of the sides of the book and to define a leaf supporting platform between the said channels, the downwardly bent portions engaging the guide members of the base to slidably secure the book holder to the base.

4. A book supporting device including a base, opposed guide members extending upwardly and outwardly from the base to thereby overhang the base, a book holder formed of sheet metal and comprising a bottom, opposed side flanges extending upwardly from the bottom to engage and support the sides of a book, said bottom being bent downwardly and inwardly at opposed points to form guide members which interfit with the guide members of the base to slidably secure the book holder to the base against vertical movement.

5. A book supporting device including a base, opposed guide members extending upwardly and outwardly from the base to thereby overhang the base, a book holder formed of sheet metal and comprising a bottom, opposed side flanges extending upwardly from the bottom to engage and support

the sides of a book, said bottom being bent downwardly and inwardly at opposed points to form guide members which interfit with the guide members of the base to slidably secure the book holder to the base against vertical movement, the lower portions of the guide members of the book holder being bent outwardly to define with the side flanges opposed channels for the reception of the lower edges of the sides of the book and to form a leaf-supporting platform between the said channels.

6. A book supporting device including a sheet metal base, guide members formed integral with the base by bending the metal upwardly at opposed points and then bending it downwardly upon itself thereby presenting a double thickness of metal, a book holder, and guide members carried by the book holder and interfitting with the guide members of the base to slidably secure the book holder to the base.

7. A book supporting device including a base, opposed longitudinally disposed guide members carried by the base, a book holder, opposed longitudinally disposed guide members carried by the book holder, the guide members of the base and book holder being spaced farther apart at one terminal than at the opposed terminal to permit the ready engagement of the book holder guide members with the base guide members.

8. A book supporting device including a base, guide members carried by the base, a book holder having an offset leaf-supporting platform, guide members carried by the book holder and cooperating with the guide members of the base to slidably secure the book holder to the base, yieldable actuating means for sliding the book holder in one direction, and means positioned between the base and the leaf-supporting platform for holding the book holder against the action of the yieldable actuating means and for releasing the book holder for sliding movement responsive to the action of the yieldable actuating means.

9. A book supporting device including a base, guide members carried by the base, a book holder, guide members carried by the book holder and cooperating with the guide members of the base to slidably secure the book holder to the base, yieldable actuating means for sliding the book holder in one direction, a spring secured to the base and normally engaging the book holder to hold the book holder against the action of the yieldable actuating means, and a manipulating finger extending from the spring beyond the book holder to permit manual disengagement of the spring from the book holder.

In testimony whereof I affix my signature.
JOSEPH M. ARMSTRONG.
